[57] CLAIM

The ornamental design for an industrial or municipal water clarifier, as shown and described.

DESCRIPTION

FIG. 1 is a front view of an industrial or municipal water clarifier;

FIG. 2 is a back view;

FIG. 3 is a left-side view, the right-side view being a mirror image thereof;

FIG. 4 is a top view;

FIG. 5 is a perspective view in which the clarifier is shown with a radial trough;

FIG. 6 is a perspective view in which the clarifier is shown with a peripheral trough;

FIG. 7 is a perspective view in which the clarifier is shown with a helical weir; and,

FIG. 8 is a perspective view of an alternate embodiment of the design in a clarifier utilizing multiple drop boxes.

The broken lines in the figures indicate possible types of observation decks and troughs or weirs that may be used with but do not form part of the design as claimed.
